UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

AUTOMATIC SWITCH.

1,238,106.

Specification of Letters Patent. Patented Aug. 28, 1917.

Application filed November 17, 1916. Serial No. 131,873.

To all whom it may concern:

Be it known that I, HENRY P. CLAUSEN, a citizen of the United States, residing at Mount Vernon, in the county of Westchester and State of New York, have invented 5 certain new and useful Improvements in Automatic Switches, of which the following is a full, clear, concise, and exact description.

10 This invention relates to automatic switches of the panel type, for automatically interconnecting telephone lines. It is adapted for use with either automatic or semi-automatic telephone exchange systems. In this 15 type of switch, sets of terminals are assembled in vertical rows in a large flat-faced bank or panel over which brushes are allowed to drop in a straight line to the desired set. These terminals are multiplied 20 horizontally across the board to be accessible to any switch.

The object of this invention is to provide new and improved means for extending a connection from a calling subscriber to an 25 idle trunk line, which trunk may lead either to a selector switch or to an operator's position.

A feature of the invention is the provision in a gravity operated switch of mechanical stops for arresting the brushes on 30 an idle trunk. Another feature of this invention is the arrangement of the terminals of the telephone lines.

Other features of the invention will be 35 apparent from the following detailed description and the appended claims.

Referring to the drawings, Figure 1 shows a side elevation of two of the switches in position to engage contacts on opposite sides 40 of the same panel board; Fig. 2 is a section on line 2-2 of Fig. 1, showing the brush carrier, brushes, bank contacts and line rods; Fig. 3 is a front elevation on the line 3-3 of Fig. 1, showing a trunk bar broken away 45 and a relay for tipping the same; Fig. 4 shows a circuit arrangement by which the switch may be operated; and Fig. 5 is a schematic representation of the connections for the trunk bar tipping magnets, showing 50 how each trunk bar appears at a different level in every group.

In the embodiment of the invention herein disclosed a switch will be provided individual to each subscriber, the switches being 55 mounted side by side in groups of any de-

sirable number. A switch is placed before each set of contacts and comprises the following parts: a vertical rod held at either end between plates, a rod slidably mounted on said vertical rod and a brush holder fixed 60 at the upper end of the hollow rod. Teeth are cut in this hollow sliding rod and two holding pawls adapted to engage the teeth are provided. One pawl is controlled by a line relay and normally engages the teeth 65 to hold the switch in its top position. The other pawl is actuated by a stepping magnet to return the switch to normal at the completion of the call. In addition to brushes, the brush carrier has a trip rod which extends backward so as to engage one of a set of cross bars which is in normal position. These cross bars represent trunks and are in position to be engaged when their associated trunks are idle, but are tipped back 70 out of the way as soon as their trunks become busy.

Adjacent to each row of bank contacts is a vertical rod, to which is connected one terminal of a subscriber's line. When a call 80 is initiated the line relay pulls up, disengaging its pawl from the sliding rod which falls under the attraction of gravity. When an idle trunk is reached, the brush tripper is engaged by the cross bar, the brushes are 85 tripped and the carriage stops. The brushes now connect each terminal contact with its adjacent line rod and the object of the invention has been accomplished. On the completion of the call, the stepping magnet 90 is intermittently energized to return the structure to its normal position, and the trunk bar is returned to its normal position ready to stop the next falling switch.

Referring now more specifically to the 95 drawings, a frame 100 is provided to hold each group of switches with its associated contact banks. Fixed to the frame 100 and to a similar frame at the bottom of the switches, are the plates 101 and another of 100 similar design not shown. These plates are provided with holes for receiving the fixed vertical rods 102 on which slide the hollow rods 103. At the upper end of each rod 103 is a brush holder 104 carrying the 105 brushes 200, 201, 202, 203, 204 and 205. At the lower end is a pin 108 for closing the off-normal contacts ON when the switch is at any position other than the top.

An angle iron 112 mounted on the frame 110

100 holds the upper end of plates 113 whose lower end may be held by a similar iron not shown. On each plate 113 are mounted relays LR, CO and RR and the magnet SM of a switch. The relays CO and RR may be mounted on the same core to save space. A portion 110 of each plate 113 is bent at right angles to the plate and a hole is cut in the bent portion to allow the passage of the rod 103 through it; but to keep said rod in its proper relation to pawls 114 and 115 of relay LR and magnet SM, respectively. Pawl 114 is normally held in engagement with teeth 109 by spring 116, but may be disengaged by catch 117, which upon energization of the relay LR is pulled up by armature 118 of said relay. Armature 118 is provided with an arm and roller 119 for operating its contact springs 120. Pawl 115 is normally held away from the teeth 109 by pin 121 but is pushed against said teeth by spring 122 when armature 123 of magnet SM is pulled up.

The trunk bars 300 extend horizontally across a group of switches and are placed so as to engage in their forward position trip rod 106 of brush carrier 104 when the switch is released. At either end of each bar 300 is an arm 304 which is pivoted on a pin 305. These pins 305 are held in plates 309 which are themselves secured to plates 310, one of which is provided at each end of the group of switches.

Near the end of each bar 300 is attached a lug 301 which is engaged by arm 302 of armature 306 of the relay 403. The bars 300 are held in normal position by springs 307 but when relays 403 pull up they are tipped back so that edges 308 will allow trip rod 106 to pass unobstructed. A bar 300 is shown in its tipped position in dotted lines in Fig. 1. The relays 403 of which one is provided for each bar are mounted on plate 311 which is located near one end of the bars 300 so as to be out of the way of the switches.

The construction of brush holder 104 will be understood by referring to Fig. 2. The brush end is bent into the shape of a yoke shown at 217, which holds the pin 107. Near the rod 103 the holder is bent to form two horizontal leaves 213. These leaves are cut to fit rod 103 and are fastened to it by clamp 105. An arm 218 extends backward parallel to trip rod 106. At the end of this arm is mounted on pin 215, a stop arm 214 which is held in its normal position by stop 219 and spring 220. The stop arm 214 during the fall of the brush carrier will engage the edge 308 of the first bar 300 which is in its forward position and will bring the brush carrier to a positive stop. The trip rod 216 is also bent to form a yoke at the brush end and is rotatably mounted on pin 107.

65 The brushes 200, 201, 202, 203, 204 and

205 are fastened to resilient arms 225 and 226 which are held onto holder 104 by bolt 222. The arms 225 and 226 are held apart by insulated washers, and by strips of insulation 223. They are sprung so as to have a tendency to close together toward the center of the brushes. They are normally prevented from closing by pins 221, carried on the yoke of trip rod 106, which hold them apart. These pins are covered at their lower ends with insulation. When end 216 of rod 106 is raised by contact with a bar 300, the pins 221 are depressed so that the insulated ends are carried below the brushes, allowing the brush arms to spring together and the brushes to rest on the rods 206, 208 and 211 and contacts 207, 209 and 210. In this position of the brushes each contact 207, 209 and 210 is in electrical connection with its adjacent rod 206, 208 or 211. The operation of the trip rod retards the movement of the brush carrier and dissipates its momentum.

The contact panel is of usual construction, the contacts and insulated layers being supported on the rod 125 and held down at the top by a similar rod 128. These rods are held together by vertical rods 124 one of which is provided at each end of the panel and are fastened to the frame as shown or in any well-known manner.

Between the rods 125 and 128 and the panel, plates 127 are inserted. Their projections 224 serve as supports for the line rods 206, 208 and 211, one of which is provided adjacent each row of contacts. These rods may be tightened by nuts 129, one of which is threaded on each rod. To each set of three line rods are connected the terminals of a subscriber's line.

Referring now to the circuit diagram, Fig. 4, the operation of the switch is as follows: When the calling subscriber removes his receiver from the hook, line relay LR is energized over the following path: 100 grounded battery, relay LR, wire 9, normal contact of off-normal contact ON, middle contact of relay CO, wires 7, 5, subscriber's set, wires 6, 8 to ground over innermost contact of relay CO. The attraction of the armature 118 of this relay disengages the pawl 114 from the teeth of the sliding rod 103, and the brush carrier falls. Off-normal contacts ON are released by pin 108 and a locking circuit for relay LR is closed over wire 10, outermost contact of relay CO, bottom spring of ON to ground. The switch falls until end 216 of trip rod 106 is engaged by a bar 300 representing an idle trunk line. The tripping of rod 106 takes up the shock of 125 stopping the carrier which is positively stopped by stop arm 214, holding against edge 308. The brushes now rest on the contacts of an idle trunk and supervisory relay 400 is energized from grounded battery over 130

the subscriber's line through sluggish supervisory relay 401 to ground. Relay 401 being a slow relay does not, however, come up immediately. Relay 400 closes at its front contact a circuit for cut-off relay CO from ground through resistance R, front contact of relay 400, contact 210, line rod 211, relay CO and battery. When the relay CO pulls up, it breaks at its outermost contact the locking circuit of the relay LR, whose armature falls back allowing pawl 114 to engage teeth 109, thus supporting the brush carrier. Slow relay 401 becomes energized as soon as relay LR has retracted its armature, and closes at its front contact a circuit for trunk bar tipping relays 403 from ground through resistance R, front contact of relay 400, front contact of relay 401, relay 403 to battery. Relays 403 now tip back their associated bars 300 preventing their seizure by any other switch. The subscriber is now in connection with an idle operator in the case of a semi-automatic system or with a selector switch in the case of a full automatic system, and the connection to the called subscriber is completed in the usual manner.

At the end of the conversation when the calling subscriber hangs up, the circuit for supervisory relays 400 and 401 is broken at the switchhook. Armature of relay 400 in falling back breaks the circuit of relay CO, whereupon restoring relay RR is energized from grounded battery through the relay, wire 11, back contact of relay LR, outermost contact of relay CO, to ground at bottom contact of ON. Relay RR closes, at its innermost contact, a circuit from ground through the stepping magnet SM, interrupter I, to grounded battery. At its middle and outermost contacts, it opens the circuit of the calling subscriber, thus preventing interference by him with restoration of the switch. The subscriber's connection with relay LR is also broken by the contacts ON which are not returned to normal until the switch is ready for the initiation of another call. Stepping magnet SM being intermittently energized returns the brush carrier to its top position, whereupon the circuit of RR is broken at ON and the switch is stopped. In passing bars 300, stop arm 214 will not tip them but will itself yield because spring 220 is made weak relative to spring 307. Just before the switch reaches normal, end 216 of trip rod 106 will strike the plate 101 thus spreading the brushes. The brushes wipe over the intervening trunk contacts during the restoration of the switch, but the resistance R is sufficient to prevent the flow of enough current through the relay CO to energize it in parallel with other relays CO or 403.

Fig. 5 shows schematically the arrangement of the trunk bars representing a given line before different panels. The bars repre-

senting a given trunk appear at a different level before each panel. If this were not the case, two switches starting simultaneously, one before panel 500 and one before panel 501, would seize the same trunk bar putting 70 the two subscribers in connection with the same trunk. By the arrangement shown, however, two switches in different groups starting simultaneously cannot seize the 75 trunk bar, for the bar representing the trunk seized by the first switch will be tipped back before the second switch reaches it.

What is claimed is:

1. In an automatic switch, a plurality of 80 terminal strips, a gravity operated brush to coöperate therewith, means for releasing said brush, and a plurality of stop members extending across the faces of said terminal strips arranged to arrest the movement of 85 a falling brush.

2. In an automatic switch, a plurality of 90 terminal strips, a gravity operated brush to coöperate therewith, means for releasing said brush and a plurality of stop members extending across the faces of said terminal strips and arranged to arrest the movement 95 of a falling brush, and means controlled by the engagement of a falling brush with a stop member for temporarily removing said 100 stop member from the path of subsequently falling brushes.

3. In an automatic switch, a plurality of 100 terminal strips, a gravity operated brush carriage adapted to traverse each of said 105 terminal strips, brushes on said brush carriage, horizontally arranged stop members extending across the faces of said terminal strips, one for each level of terminals, said stop members being adapted to arrest the movement of a falling brush carriage, means controlled by the engagement of a brush carriage with a stop member for moving the brushes thereof into engagement with the corresponding terminals, and means operated upon the engagement of the brushes with the terminals for temporarily removing said stop members from the path of subsequently falling brushes.

4. In an automatic switch, sets of fixed 115 terminals, a plurality of gravity operated brushes arranged to travel over and make contact with said terminals, means for normally maintaining said brushes inoperative with respect to said terminals, a plurality 120 of mechanical stops each associated with a transverse set of terminals for arresting said shaft and rendering said brushes operative with respect to said terminals, and means for actuating said stops, said means being 125 responsive to the electrical condition of the terminals associated with said stops.

5. In an automatic switch, the combination with a row of contact sets, a longitudinally movable brush carrier, means for 130

- moving said carrier, a brush holder on said carrier, a plurality of brushes for traversing said contact sets, resilient arms for uniting said brushes to said holder, a trip rod yieldingly mounted on said holder, said trip rod normally flexing said arms to hold the brushes inoperative, a spring pressed stop arm pivotally mounted on said holder, a plurality of mechanical stops, and means for 5 positioning said stops to engage said stop arm and trip rod in their travel, said trip rod when engaged absorbing the momentum of said brush carrier and tripping the brushes and said stop arm when engaged bringing 10 said carrier to a positive stop with its brushes resting on a set of contacts.
6. In an automatic switch, a plurality of vertically arranged terminal strips, the terminal of each strip being multiplied to different levels in the other strips, a gravity 15 operated brush carriage adapted to traverse each of said terminal strips, horizontally arranged stop bars extending across the faces of said terminal strips one for each 20 level of terminals, said stop bars being adapted to arrest the movement of a falling brush carriage, and means operated upon the engagement of a brush carriage with a 25 stop bar for temporarily removing the engaged stop bar and the stop bars of the multiplied terminals in other strips from the 30 path of movement of subsequently operated brushes.
7. In an automatic switch, a plurality of vertically arranged terminal strips, the terminal of each strip being multiplied to different levels in the other strips, a gravity operated brush carriage adapted to traverse each of said terminal strips, a plurality of 35 horizontally arranged stop bars extending across the faces of said terminal strips one for each level of terminals, said stop bars being adapted to arrest the movement of a 40

falling brush carriage, an electromagnet individual to each stop bar, those magnets associated with bars representing multiples of the same terminal being electrically connected so as to be energized simultaneously, said magnets when energized removing their associated stop bars from the path of movement of the brushes, and means operated upon the engagement of a brush carriage with a stop bar for energizing said magnets. 45

8. In an automatic switch, a plurality of vertically arranged terminal strips, a plurality of gravity operated brushes adapted to traverse said terminal strips, means for normally retaining said brushes at rest, means for releasing any one of said brushes, means for stopping said brush on a selected 50 strip, means operated upon the stopping of said brush for actuating said normal retaining means, and means operated upon the actuation of said retaining means for temporarily removing said stopping means from 55 the path of subsequently falling brushes. 60

9. In a telephone exchange system, a group of lines, sets of terminals in which said lines terminate, said sets of terminals being arranged in rows, a second group of 70 lines, rods in which said second group of lines terminate, said rods being interspersed between the said terminals and arranged in a direction parallel to said rows of terminals, said rods and said rows of terminals being 75 equal in number, a set of brushes arranged to travel over and make contact between said rods and the terminals adjacent thereto, means for normally preventing said brushes from making said connection, and means for rendering said means ineffective. 80

In witness whereof, I hereunto subscribe my name this 16th day of November A. D., 1916.

HENRY P. CLAUSEN.
